UNITED STATES PATENT OFFICE.

AUSTIN F. JACKSON, OF TAUNTON, MASSACHUSETTS.

DESIGN FOR A HANDLE FOR SPOONS, FORKS, LADLES, &c.

SPECIFICATION forming part of Design No. 32,467, dated April 10, 1900.

Application filed March 14, 1900. Serial No. 8,677. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for the Handles of Spoons, Forks, Ladles, and Kindred Articles, of which the following is a specification, reference being had to the accompanying drawings, forming part thereof, and in which—

Figure 1 is an obverse and Fig. 2 a reverse elevation of a spoon, showing my new design, the tines of a fork being indicated by dotted lines in both figures.

As shown in the drawings, the leading or material feature of my design consists in the design forming the subject-matter of the accompanying illustration.

The handle A has the narrow shank A', which swells out laterally at B and widens 20 gradually at C toward the end of the handle. Ribs D extend longitudinally along the edge of the handle, and the obverse is ornamented, as shown in Fig. 1, by scrolls E at the end of the handle, scrolls F upon the portion C, and 25 a row of beads extending along the shank A'.

Having described my invention, what I claim as new, and desire to secure by Letters Patent, is—

The design for a handle for spoons, forks, 30 ladles and kindred articles, as herein shown and described.

AUSTIN F. JACKSON.
